UNITED STATES PATENT OFFICE

GEORG SPIESS, OF LEIPZIG, GERMANY

PLATEN PRINTING PRESS

Application filed June 12, 1929, Serial No. 370,311, and in Germany May 16, 1928.

The invention relates to platen printing presses wherein an ink distributing roller or cylinder is reciprocated together with its inking rollers, and means are provided for removing the inking rollers from the cylinder. Certain risks attend the removal of the inking rollers from the cylinder while the latter is in operation. Generally the throw-off device for the inking rollers comprises cams acting on spring pressed shanks fixed to slidable bearings of the rollers, and if these are actuated while the cylinder is in operation an additional load is suddenly thrown on the cylinder, and the spring shanks are subjected to a sudden bending stress, which may easily cause damage.

The object of my invention is to provide improved means for removing this risk, and to this end I provide a device which automatically restrains the throw-off device from operating while the distributing cylinder is in operation.

A preferred constructional form of a device according to the invention is illustrated by way of example in the accompanying drawings, in which all details of the platen printing press not necessary for the explanation of the invention are omitted.

In the drawings

Fig. 1 is a view in elevation of the throw-off device of the inking rollers according to the invention and

Fig. 1a is a view looking from the front toward one of the vertical guides and showing the raised position of the detent.

Fig. 1b is a similar view showing the lowered position of the detent.

Fig. 2 is a modification.

The press has two vertical guides 1 with channels 2 for guiding the holder 3 of the cylinder. The inking rollers 5 are mounted on the holder 3 by means of horizontally movable bearings, with springs pulling the rollers towards the circumference of the contact cylinder 7. Distributing rollers 8 act on the circumference of the cylinder, and there may be an additional inking roller 9, to which a doctor 10 supplies ink.

A bar 11 is horizontally slidable in each

of the guides 1 for removing the inking rollers from the cylinder, each bar 11 having a head 12 which acts on the shanks 6 of the inking roller bearings when the bar 11 is moved as indicated by the arrow, whereby the springs are compressed.

Each bar 11 has two cam faces 13, for lifting rods 14, 15 connected to the bearings of the rollers 9 and 8. The rods 14 and 15 work in guides in the side frames.

At the top of the head 12 there is pivoted a pawl 17, acted on by a spring 18 so that normally a projection of the pawl is pressed against a surface 19 of the head 12. The pawl 17 is adapted to engage an abutment 4 on the holder 3, when the bar 11 is moved towards the holder, the bar 11 being by this means locked in the position in which the inking rollers 5, the spreading rollers 8 and the inking roller 9 are removed from the cylinder 7. By the downward movement of the holder 3 the abutment 4 is removed from pawl 17, so that the bar 11 is released, and the shanks 6 acting on the head 12, with the rods 14, 15 acting on the cam surfaces 13, push the bar 11 back, assisted by a spring 24 acting on a lever 25, which rotates on a spindle 31 and is engaged with the bar.

Two levers 21 connected by a hand bar 22 are pivoted on the spindle 31 and have noses 23, adapted to coact with noses 32 on the levers 25 for rocking the latter and moving the bar 11 as indicated by the arrow. Levers 20 pivoted to the levers 21 rest on the pawl 17, and when the bar 11 has been moved to remove the rollers 5, 8, 9 from the cylinder 7 the free ends of the levers 20 rest only on the tails of the pawls, so that by depressing the levers 20 the pawls can be disengaged from the abutments 4. The levers 20 are depressed by projections 30 on the levers 21, when the latter are rocked in the opposite direction to that indicated by a curved arrow in the drawing.

At the upper end of each guide channel 2 there is a slidable detent block 26 normally held by gravity and by a spring 27 against a stop 28, but this block is slightly lifted by the holder 3 each time the latter ascends. A

stop 29 projecting from the lower end of the block 26 is exactly in the path of the pawl 17 when the block 26 is lowered, so that it prevents the bar 11 from making the movement which throws off the inking rollers. If from some accidental cause the throw-off bar 11 fails to return to its normal position after disengagement of the pawl 17 and after descent of the distributing cylinder, damage might occur through the shanks 6 striking the head 12 of the bar, if it remained in their path, but this is prevented by providing the head 12 with a cam 16, which in the circumstances mentioned is struck by the abutment 4 when the holder 3 ascends, so that the head is pushed out of the way of the shanks 6, the stop 29 being then placed in the path of the pawl 17.

In Fig. 1. the throw-off device is shown in its inactive position. The inking rollers 5 are in contact with the inking cylinder 7. The roller carriage, by means of guide part 3a, moving in guide channel 2, lifts up detent 26, projecting into the same guide channel. Stop 29, therefore, is no longer opposite pawl 17. With the roller carriage in the aforesaid position the roller-removing-device is ready for operation. Pawl 17 engages behind abutment 4 of the roller carriage, locking thereby the roller-removing-device in its removing position. Upon lowering the roller carriage the abutment 4 of the roller carriage separates from pawl 17 and the throw-off device moves automatically under the action of spring 24 back to normal or inactive position. If, for some reason or another the return movement is interfered with, then the abutment 4 strikes against the upper part of cam 16, forcing thereby the throw-off device to return to its normal position. The roller carriage is followed in its downward movement by detent 26, whereupon projection 26a rests upon abutment 28. Stop 29, then, is again locked opposite of pawl 17. Detent 26, consequently, prevents operation of the removing device when the roller carriage is lowered.

According to the modification shown in Fig. 2 the manual controlling means for the throw-off device are placed laterally at the front of the press. Generally it is convenient to have separate hand levers, for actuation and disengagement respectively.

Forked arms 25 engaging studs on the throw-off bars 11 for the inking rollers on the vertically movable holder or carriage 3 of the distributing cylinder are fixed to a rock shaft 33 mounted in the bed frame, and to the rock shaft is fixed a lever 34 extending towards the front of the press. The upper, front part of the frame has two forwardly projecting arms 35, in which is mounted a rock shaft 36. To each end of the latter is fixed an arm 37 adapted to rest on the holder 3 when the holder is in its

upper end position. The arms 37 have wedge shaped ends 38, which engage under the pawl 17 pivoted to the head 12 of the bars 11, when the said pawls have been moved into engagement with abutments on the holder 3, after advancing the bars 11 to throw off the inking rollers. One of the arms 37 has a handle 39, for rocking the shaft 36 with the two arms 37 in order to disengage the pawls. 75

What I claim is:—

1. Platen press inking mechanism having distributing rollers reciprocating together with inking rollers, and a throw-off device for said inking rollers, with a device automatically restraining said throw-off device from operation while the distributing roller is in operation. 80

2. Mechanism according to claim 1, wherein the device restraining the throw-off device from operation is put out of action by a moving part of the press when the holder or carriage of the inking roller reaches its end position. 85

3. Mechanism according to claim 1, 90 wherein the throw-off device has cam surfaces and the holder of the inking cylinders has an abutment adapted to act on said cam surfaces for restoring the throw-off device to its inactive position. 95

4. Mechanism according to claim 1, 100 wherein means for manual actuation of the throw-off device for the inking rollers, is disposed at the front of the machine.

5. Mechanism according to claim 1, having 105 separate hand levers for the actuation and the retraction of the throw-off device respectively.

In testimony whereof I affix my signature.
